UNITED STATES PATENT OFFICE

115,559

DESIGN FOR AN AUTOMOBILE GRILLE GUARD

Louis A. Koch, Louisville, Ky.

Application February 21, 1939, Serial No. 83,131

Term of patent 7 years

To all whom it may concern:

Be it known that I, Louis A. Koch, a citizen of the United States, residing at Louisville, in the county of Jefferson and State of Kentucky, have invented a new, original, and ornamental Design for an Automobile Grille Guard, of which the following is a specification, reference being had to the accompanying drawing, forming a part thereof.

In said drawing:

The characteristic features of my design are shown in solid black lines in the drawing.

I claim:

The ornamental design for an automobile grille guard, as shown and described.

LOUIS A. KOCH.
